TO BUTTONLATH MANUFACTURING COMPANY, OF LOS ANGELES, CALIFORNIA, A
CORPORATION OF CALIFORNIA.

PLASTER-LATH.

1,205,360.

Specification of Letters Patent. Patented Nov. 21, 1916.

Application filed June 28, 1915. Serial No. 36,790.

To all whom it may concern:

Be it known that we, HENRY LA CASSE and JAMES P. SEXTON, citizens of the United States, residing at Los Angeles, in the county of Los Angeles, State of California, have invented new and useful Improvements in Plaster-Laths, of which the following is a specification.

This invention relates to certain improvements over Patent No. 1,115,593, granted Nov. 3rd, 1914, to James P. Sexton, and to improvements to an application co-pending herewith by the said Sexton being application Serial No. 36657, filed June 22nd, 1915; and the improvements herein specified relate particularly to the construction and formation of the cementitious buttons and of the facing sheet in plaster lath or the like, with the object of producing a strong and durable lath to which plaster may be applied in such manner as to form a permanently strong construction.

The details and specific improvements involved in this invention are particularly explained in detail in the following specification, reference being had to the accompanying drawings, in which we have illustrated preferred forms of our present invention, and in which drawings—

Figure 1 is a section of one form of our improved plaster lath, Fig. 2 is a section showing a double faced form of the same, Fig. 3 is a plan of our improved form of plaster lath, Fig. 4 is an enlarged section showing the formation of the facing sheets in detail, and Fig. 5 is an enlarged fragmentary plan of the same.

It will be understood that our improved construction may be made either in single faced or double faced form as is illustrated in Figs. 1 and 2. In Fig. 1 the cementitious body 10 is faced by two form members 11 and 12, the facing sheet 11 forming the front form member being constructed as hereinafter described, while the back sheet 12 is a plain flat sheet. In Fig. 2 we have shown both members 11 and 12^a constructed in the same manner, so as to form a double faced plaster lath to which plaster may be applied on opposite faces for the formation of a thin double faced partition.

The face sheets 11 and 12^a are made as shown in detail in the various views. Spaced depressions or recesses 15 are formed over

the face sheets, these depressions being preferably circular and spaced at about the distances illustrated. These depressions are comparatively shallow and have sloping sides 16 as illustrated; and at the center of each depression there is a circular opening 17 which is preferably formed in the manner hereinafter described. Heretofore the opening 17 has been formed as an aperture in the bottom of the depression by simply striking out the material to form an aperture of suitable size. We now prefer to form the opening 17 by splitting the material within the outlines of the opening into a plurality of tongues 18 which are then turned upwardly and slightly outwardly 70 from each other, as is clearly shown in Figs. 1, 2 and 4. At the same time a bead 19 is formed around the opening, so that a portion of the material of the lips 18 is taken up in this bead, and so that the upper ends 75 of the tongues are made to stand approximately in the plane of the face of the face sheet. This operation is facilitated by separating the tongues somewhat back into the bead, as is illustrated at 20 in Figs. 4 and 80 5; the formation of the bead then taking up some of the length of the tongues (the length of the tongue being equivalent to the radius of the openings 17, except as that length is taken up by the formation of the 85 bead.)

There are several advantages in using the material which is struck up to form the opening 17. In the first place, the tongues 18, struck up from this material, form very 90 effectual reinforcements for the buttons 25 which are subsequently formed between and around the tongues 18; and the tongues also perform a very valuable and effective service during the formation of the plaster lath, 95 as will hereinafter be described. The beads 19 materially strengthen and stiffen the bottoms of the depressions, as is apparent, and prevent the deformation or displacement of these bottoms during the formation of the 100 plaster lath.

The preferred method of formation of the plaster lath involves the placement of the face sheet 11 face downwardly on a smooth flat surface and the application of the cementitious substance 10 over the back of the face sheet, the cementitious substance being of such consistency that it runs to some ex-

tent through the openings 17; and the cementitious substance is then pressed or smoothed out to a layer of uniform thickness, with the result that it is pressed 5 through the openings 17 to form the buttons 25 in the configuration shown in the drawings. The lips 18 perform several services during this process of formation: they reinforce the finished button as hereinbefore 10 stated; they form a guide through which the cementitious substance is pressed downwardly, thus being conducive to the correct and smooth circular formation of the buttons; and they also materially aid in the formation 15 of the button in dovetailed or key-shaped section. It will be noted that the openings 18^a between the tongues are widest at their outer ends; and it will be understood that consequently when the cementitious substance flows or is forced through 20 the opening 17 and between the tongues 18 and outwardly through the openings between the tongues, the outward flow will take place most largely near the outer ends 25 of the tongues, thereby forming a button of larger diameter at its outer end than at its inner end. This is an important feature of improvement, as this action, together with the action of flattening the outer end of the 30 button against the smooth flat surface on which the plaster lath is formed, forms a button with a sufficiently overhanging outer edge or periphery to make a good dovetail or key-shape for the applied superimposed 35 plaster to set around and form a good and strong and durable mechanical bond. Thus, in this improved form of plaster lath, the buttons are not only reinforced and strongly joined to the body or base 10 of the cementitious substance, and all the parts of the 40 plaster lath, including the face sheets 11 and 12 and the body 10, are not only strongly

joined together by the embedding of the tongues 18 in the buttons 25, but the buttons are so formed that an equally strong bond 45 is made with the applied superimposed plaster.

Having described a preferred form of our invention, we claim:

1. In a plaster lath, a perforated facing 50 sheet having surface depressions and apertures therethrough in the bottoms of the depressions, and having reinforcing tongues extending outwardly from the bottoms of the depressions into the depressions around 55 the apertures, and a cementitious base back of the facing sheet projecting through the apertures to form protrusions extending into the depressions and about the reinforcing tongues. 60

2. In a plaster lath, a perforated facing sheet having surface depressions and apertures therethrough in the bottoms of the depressions, and having reinforcing tongues 65 extending outwardly from the bottoms of the depressions into the depressions around the apertures, said tongues being integral with the facing sheet and formed of the material struck out of the facing sheet to form the apertures, and a cementitious base back 70 of the facing sheet projecting through the apertures to form protrusions extending into the depressions and about the reinforcing tongues. 75

In witness that we claim the foregoing we have hereunto subscribed our names this 17th and 18th days of June, 1915, respectively.

HENRY LA CASSE.
JAMES P. SEXTON.
